(57) **CLAIM**

The ornamental design for an information band for firearm, as shown and described.

DESCRIPTION

FIG. 1 is a perspective view of a first embodiment of the information band for firearm showing my new design.

FIG. 2 is a front elevation view thereof.

FIG. 3 is a left side elevation view thereof.

FIG. 4 is a top plan view thereof; the bottom view being the same.

FIG. 5 is a right side elevation view thereof.

FIG. 6 is a perspective view of a second embodiment of the information band for firearm showing my new design.

FIG. 7 is a front elevation view thereof.

FIG. 8 is a left side elevation view thereof.

FIG. 9 is a top plan view thereof; the bottom view being the same.

FIG. 10 is a right side elevation view thereof.

FIG. 11 is a perspective view of a third embodiment of the information band for firearm showing my new design.

FIG. 12 is a front elevation view thereof.

FIG. 13 is a left side elevation view thereof.

FIG. 14 is a right side elevation view thereof; and,

FIG. 15 is a top plan view thereof; the bottom view being the same.
